UNITED STATES PATENT OFFICE.

ELISE SCHWARZ-BERCHENMEIER, OF ST. GALLEN, SWITZERLAND.

EDGE REENFORCER FOR HOSIERY.

Application filed April 23, 1921. Serial No. 463,813.

To all whom it may concern:

Be it known that I, ELISE SCHWARZ-BERCHENMEIER, a citizen of Switzerland, residing at St. Gallen, Switzerland, have invented certain new and useful Improvements in Edge Reenforcers for Hosiery, of which the following is a specification.

My invention has reference to a new and improved means for reinforcing the top or edge portion of stockings, socks or hose where the clasp of the hose supporter engages the fabric, and it relates more particularly to a reinforcing unit which can readily be attached to a finished stocking, which, when the latter is finally worn out, can be detached and used again on a new stocking, the material of which is, in part, of a stretchable character, so as not to interfere with the "give" thereof under stress, such as is now the case in similar devices where the unyielding, stiff portion is apt to cause irritation of the skin of the wearer and places additional stress on the stocking fabric; and the object of the invention is to provide a cheap and tearproof protecting attachment which can be bought by itself and then can readily be attached to the hose, though it may, obviously, be attached already by the hose manufacturer, and which can be used over and over on the stocking proper wearing out.

In order to make my invention more readily understood, I will now describe it in detail in connection with the accompanying sheet of drawings, in which Fig. 1 is a front elevation of the simplest embodiment of my invention, in position on a stocking fragment; Fig. 2 is a section on line 2—2 of Fig. 1; Fig. 3 a somewhat perspective view of an attachment showing two tabs; Fig. 4 shows the stiffening annulus, and Fig. 5 an edge view, partly in section, of the two-tabbed device secured to the edge of a stocking and gripped by the clasp member of a hose supporter.

The protector essentially comprises the head portion 1, in the shape of an annulus,

and the flat tab portion 2. The tab is to be woven of a material which stretches with the stocking material so that the attachment 50 tab and underlying stocking portion, when united by stitches, act as one. The head portion 1 I prefer to make stiff enough to retain its shape under conditions of use and disuse, and I obtain this by using as foundation a stiffening annulus 3 of suitable material, such as non-corroding metal, bone, fiber, or the like, and by then completely enveloping this stiffening member by embroidery work 4. This embroidery work is 60 carried down to join the upper edge of the woven tab 2, as at 4', combining the two portions into an integral unit, whose upper portion is non-stretchable and indeformable as to the annulus feature and whose lower 65 portion is readily stretchable for the purposes explained above.

In Fig. 2 there is shown only one tab 2, whilst in Fig. 3 two such tabs, 2 and 2' are used to clasp between them the edge portion 5 of the stocking, as shown in Fig. 5, which also shows the manner of attaching the supporter 6 by inserting the button 7 through the annulus portion 1. The tab or tabs are secured to the hose preferably by a row of 75 stitches 8.

What I claim is:—

1. An edge reenforcer for hosiery, comprising a stretchable tab portion adapted to be secured to and to be stretchable with the 80 hose, and an annular head portion of embroidery united with the tab portion by the embroidery stitching.

2. An edge reenforcer for hosiery, comprising a stretchable tab portion adapted to be secured to and to be stretchable with the 85 hose, and a head portion consisting of a rigid ring, and an embroidery covering concealing the ring and extended radially at one side toward the tab and secured thereto by 90 the embroidery stitching.

In testimony whereof I affix my signature.

ELISE SCHWARZ-BERCHENMEIER.
